UNITED STATES PATENT OFFICE.

CARL G. PRITCHARD, OF WARREN, OHIO, ASSIGNOR TO THE HARRIS AUTOMATIC PRESS COMPANY, OF NILES, OHIO, A CORPORATION OF OHIO.

PRINTING-PRESS.

1,301,970.

Specification of Letters Patent. Patented Apr. 29, 1919.

Application filed February 12, 1916. Serial No. 77,818.

To all whom it may concern:

Be it known that I, CARL G. PRITCHARD, a citizen of the United States, and a resident of Warren, in the county of Trumbull and 5 State of Ohio, have invented certain new and useful Improvements in Printing Presses, of which the following is a specification.

My invention relates to printing-presses, and the invention is embodied in improvements for separating the printing or other coacting members of the press, and also in improved devices for throwing off the inking rollers in such a printing-press, controlled but not operated by the mechanism 15 devised for the throwing off of the impression, and also in any such predetermined relation therewith, as may be desired.

The objects of my invention are, among other things, to provide a press of this general character of a simple and efficient construction, whereby the means devised for separating the printing members and for throwing off the inking rollers may be controlled and actuated, either independently 25 of the impression throw-off, or by automatic mechanism operated by the further movement or rotation of the press in its normal operation after the initial throw-off.

My improved construction also presents other features of novelty and usefulness 30 whereby the operating mechanism is rendered stronger and more durable and otherwise better adapted and more convenient for use, all of which will be hereinafter set forth and claimed.

The accompanying drawings referred to herein, and forming a part thereof, show several embodiments of the invention in "off-set" presses, the same serving, in connection with the description herein, to fully 40 explain the invention, which is not restricted, however, to any particular form or type of printing-press construction.

Of the drawings, Figure 1 is a side elevation view showing so much of a rotary off-set printing-press as is necessary to illustrate my invention;

Fig. 2 is a view similar to Fig. 1, with the three cylinders separated;

50 Fig. 3 is an elevation view with the upper part of the frame broken away to show the inking rolls raised from the form-cylinder;

Fig. 4 is a view similar to Fig. 1, showing a modified embodiment of my invention; 55

Fig. 5 is a view similar to Fig. 4, with the transfer-cylinder separated from the form-cylinder;

Fig. 6 is a view similar to Fig. 4, with the cylinders separated and the inking rolls 60 raised from the form-cylinder;

Fig. 7 is a view similar to Fig. 4, showing a second modified embodiment of my invention;

Fig. 8 is a view similar to that shown in 65 Fig. 5 in the arrangement shown in Fig. 7, the form and transfer cylinders being separated;

Figs. 9, 12 and 13 are side elevation views showing different modified embodiments of 70 my invention in "off-set" presses, which will be hereinafter set forth;

Fig. 10 is a side elevation view showing a form of tripping mechanism; and

Fig. 11 is an end view, partly in cross-section, of the tripping mechanism illustrated 75 in Fig. 10.

Similar numerals refer to similar parts throughout the several figures.

Referring more particularly to the embodiment shown in Figs. 1, 2 and 3, the frame 12 supports the bearings for the form-cylinder 13, the transfer-cylinder 14 and the impression-cylinder 15, said cylinders being mounted on the shafts 16, 17 and 18 respectively. The cylinders are so constructed and arranged in the frame 12 that the transfer-cylinder 14 forming the printing couple with the impression-cylinder 15, receives its design from the form-cylinder 90 13. The form, transfer and impression cylinders have each fastened thereto suitable gears whose pitch-diameter coincides with the periphery of the respective cylinders. These gears intermesh and form the driving mechanism to secure proper rotation for the cylinders. The power is derived from the usual pulley shaft, which is connected to the cylinder gears by a compound gear train. Since these are common forms of printing- 95 press construction and are well known in the art, they are not shown in the drawings.

The shaft 17 carrying the transfer-cylinder 14 is mounted at both ends in the eccentric bearings 19, which, in turn, are mounted 100 105 in the journals 20^a secured to the frame 12.

The bearings 19 have arms 20 projecting from flanges on the outside of the frame 12, as shown on one side thereof. The toggle levers 21 and 22 connect the outer end of the 5 arm 20 to the frame, the lever 21 being journaled to the outer end of the arm 20, while the lever 22 is pivoted to the frame at 23. The coil spring 24 connects the arm 21 to the frame 12, as shown, the spring being 10 strained when the toggle is straightened. Connected to the outer end of the lever 22 is the link 25, the other end of which is pivoted to the arm 26 mounted on the oscillating shaft 27, which may be actuated by the 15 spring 24, or through a coil spring (not shown) mounted upon the shaft 27 itself. The hand lever 28 carrying the lug 29 is arranged to co-act with the lug 30 secured to the shaft 27 to restore the impression. 20 The shaft 27 is held in the position shown in Fig. 1 by the latch 31 pivoted on the shaft 32 in the bracket 33, which latch 31 engages a notch 34 in the sleeve 35 mounted on the shaft 27, as shown in detail in Figs. 10 25 and 11.

Preferably this latch 31 would be released automatically through the trip mechanism on the feeder, which is particularly shown in Figs. 10, and 11. In these views, 36 designates the feed-table and 37 is the stock that is being fed to the press. Extending transversely above the feed-table 36 and journaled to uprights on the sides thereof, is the shaft 38 which carries the arm 38 (Fig. 35 10) connected by the rod 39 to the shaft 18 of the impression-cylinder 15 by any suitable means, so as to impart to the shaft 38 an oscillating movement. 40, 40 indicate grooved collars rigidly secured to the shaft 40 38. Adjacent each grooved collar 40 is the disk 41 affixed to the end of the tubular shaft 42 which is loosely sleeved on, and incloses a portion of, the shaft 38, as shown in Fig. 11. The shaft 42 carries the arm 43, the 45 outer end of which engages with the arm 44 mounted on the block 45 secured to the shaft 32.

46 indicates the trip-lever pivoted at 47 between the parallel sides of the grooved 50 collars 40, so that its longer and heavier arm is held from falling into the aperture 48 cut in the top of the feed-table 36 by the interposition of the stock 37, as shown in Figs. 10 and 11. At the opposite end the 55 lever 46 is T-shaped to form the tooth 49, and in the peripheries of the sides of the collar 40, and also in the periphery of the disk 41, are formed cut-outs 50 and 51 respectively. Ordinarily the tooth 49 rests 60 against, or is in proximity to, the periphery of the disk 41; it can engage with the cut-out 50 of the collar 40 only when it can fall into the cut-out 51 of the disk 41. When this occurs, the disk 41 with its shaft 42, which are normally at rest, are locked to and turn with the oscillating shaft 38. The entrance of this tooth 49 into locking engagement with the disk 41 will occur upon the failure or interruption in the feed supply. When the stock 37 is in proper position, as shown in Figs. 10 and 11, the curved longer arm of the trip-lever 46 will engage therewith and will be prevented from lowering into the aperture 48, and from turning sufficiently to interlock with the disk 41. If the stock 37 should, at any time, be interrupted or absent, the longer arm of the trip-lever 46 will fall of its own weight, into the aperture 48, thereby causing the tooth 49 to interlock with the cut-out 51 in the disk. 8 Thus the tubular shaft 42 will be caused to oscillate with the shaft 38 so as to cause the arm 43 to lift the arm 44 to release the latch 31 engaging the notch 34 in the sleeve 35 on the shaft 27. Through this movement 8 of this herein described mechanisms, the spring-impelled shaft 27 is partially rotated to swing the eccentric bearing 19 to throw off the impression by separating the transfer cylinder 14, from the form-cylinder 13 91 and impression-cylinder as shown in Fig. 2, all controlled automatically by the stock.

52 designate a series of inking rollers mounted upon a series of transverse shafts 53 carried in the slotted bearings 54. Each 95 inking roller 52 has a cylindrical bearing 55, concentric with its shaft 53, adapted to be engaged by suitably shaped cam-surfaces 56 formed in the upper portion of the rocking cam 57 loosely mounted on the shaft 16 of 101 the form-cylinder 13, the bearings 55 riding upon the high part of the cam 57 to lift the inking rollers from the form-cylinder 13, as shown in Fig. 3. The rocking movement of the cam 57 is accomplished by the following mechanism: 58 indicates a rock-lever pivoted at 59 to the frame 12, so constructed and arranged that its outer end 60 may be pushed downwardly by the lug 61 preferably mounted on the periphery of 110 the transfer-cylinder 14 through the rotation of this cylinder when separated from the form and transfer cylinder, as shown in Fig. 2, whenever the throw-off of the impression occurs. When the three cylinders 115 are in printing relation, as shown in Fig. 1, the path of rotating lug 61 will be such as to avoid engaging with the end 60 of the lever 58. Instead of being affixed to the periphery of the cylinder 14, the lug 61 120 may be mounted on the cylinder shaft 17, or on the cylinder gear, either inside or outside the frame 12. However, its location upon the transfer-cylinder itself, as shown, is preferably the most convenient arrangement in press construction. The opposite end 62 of the lever 58 is connected by the link 63 with the lever 64 pivoted at 65 in the frame 12, the outer arm 66 of which forms a latch in conjunction with the notch 130

67 in the collar 68 mounted on the shaft 69, journaled in the frame 12, which shaft 69 is adapted to be partially rotated upon the release of the latch 66 through a coil 5 spring 70, one end of which is secured to the outer end of the arm 71 mounted on the shaft 69, and the other end to the pin 72 in the frame 12. Other suitable means for securing a partial rotation of the shaft 69 10 may be utilized such as the usual spring coiled about the shaft itself. The flange 73 secured to the cam 57 carries a pin 74 which engages and co-acts with the socket 75 formed in the outer end of the arm 71, as shown. The coil spring 76 secured to a lug 77 on the link 63, and also to the pin 78 in the frame 12, serves to hold the latch 66 in engagement with the notch 67, until this latch is released by the engagement of 15 the rotating lug 61 with the arm 60, as shown in Fig. 3. If desired, the hand-lever 79 mounted on the shaft 69 may be used as a means for re-setting this shaft 69 by the engagement of the latch 66 with the notch 67 in the collar 68, the lug 80 on the handle 25 79 co-acting with the lug 81 mounted on the collar 68 to accomplish this purpose.

The operation of the hereinbefore described mechanism is substantially as follows: Whenever the stock 37 is interrupted or is absent from the feed table, the trip-lever 46 acts to release the latch 31 which causes a partial rotation of the spring-impelled shaft 27, the arm 26 moving to the right, as shown in Fig. 2, which breaks the toggle-levers 21 and 22 through the link connection 25. The breaking of this toggle connection immediately causes the arm 20 to swing upwardly, as shown in Fig. 2, which causes the transfer-cylinder 14 to move obliquely in its eccentric bearings 19 away from both form-cylinder 13 and impression-cylinder 15, thereby breaking the printing relation of the three cylinders, and throwing off the impression, all as shown in Fig. 2. It will be noted from the action of the press as shown in Fig. 2, that while the impression throw-off has taken place, the inking rollers 52 have not as yet been tripped to 40 throw same from the form-cylinder 13, the lug 61 being about to engage the outer end 60 of the rock-lever 58. As the transfer-cylinder 14 continues its clock-wise rotation in the rotation of the press, the lug 61 through its engagement with the end 60, rocks the lever 58 which, through the link 63, rocks the lever 64 to release the latch 66 from its engagement with the notch 67 formed in the collar 68. The shaft 69 is then 45 partially rotated in a clock-wise direction through the action of the coil spring 70 acting on the outer end of the arm 71 mounted on the shaft, and lifts the flange 73 secured to the cam 57, causing the latter to rock on 50 the form-cylinder shaft 16 toward the left,

whereby the inking rollers 52 are lifted from the form-cylinder 13 through the roller bearings 55 riding upwardly on the high part of the cam-surfaces 56 in the cam 57, all as shown in Fig. 3. The hand-lever 28 is lifted 70 to restore the printing relation of the cylinders and the engagement of the latch 31 with the notch 34, and in like manner the hand-lever 79 is raised to reset the latch 66, whereby the outer end 60 of the rock-lever 58 is lowered beyond the path of the lug 61, as the transfer-cylinder is rotated, as shown 75 by the arrows, when printing relation is restored.

It is obvious from the construction and operation of this mechanism, as herein shown and described, that the inking rollers may be thrown off from the form-cylinder by means actuated independently of the impression throw-off, and also by means automatically operated through the continued movement of the press.

In the embodiment of my invention illustrated in Figs. 4, 5 and 6, I employ the same mechanism for throwing off the inking rollers 52, as has been shown and described with reference to the embodiment illustrated in Figs. 1, 2 and 3, but the modification is made in the construction utilized for accomplishing the throw-off of the transfer-cylinder 14. Fig. 4 shows all three cylinders in contact; Fig. 5 shows the transfer-cylinder 14 separated from the form-cylinder 13, but remaining in contact with the impression-cylinder 15; and Fig. 6 shows the cylinder 14 separated from all three cylinders and the inking rollers out of contact with the form-cylinder 13. This arrangement first separates the form-cylinder 13 and transfer-cylinder 14 to prevent inking the blanket on 100 the transfer-cylinder, and subsequently the printing impression and the inking rollers are thrown off.

Referring to the construction shown in Figs. 4, 5 and 6, the shaft 17 of the transfer-cylinder 14 is mounted in the eccentric bearings 19. The shaft 17 is also mounted in the journal-box 82 mounted to slide radially on the ways 83 in the frame 12 to and from the impression-cylinder 15. The compression 115 spring 84 is secured in the opening 85 formed in the frame 12 to normally force the journal-box 82 outwardly, so as to separate the transfer-cylinder 14 from the impression cylinder 15. The transfer-cylinder 120 14 is held in contact with the impression-cylinder 15 against the tension of the spring 84 by the following mechanism: Pivoted at 85 to the frame 12 is the rock-lever 86, the outer end 87 of which is arranged to be engaged by the rotating lug 88 mounted on the cylinder 14, in the same manner as the rotating lug 61 so as to engage the outer end 87 of the rock-lever 86 through the rotation of 125 the transfer-cylinder 14 when it is separated 130

from the form-cylinder 13, as shown in Figs. 5 and 6. The opposite end 89 of the rock-lever 86 constitutes a latch which engages in a notch 90 formed in the collar 91 mounted 5 on the oscillating shaft 92 journaled in the frame 12. Secured to the shaft 92 is the arm 93 to which is fastened the coil spring 94, attached to the frame 12 by the pin 95. The arm 93 is pivotally connected at 95^a with the 10 arm 96 journaled in the bracket 97 carried on the journal-box 82, the arms 93 and 96 forming a straight toggle connection between the journal-box 82 and the shaft 92 when the latch 89 is in locking engagement 15 with the notch 90, the spring 94 being strained. The spring 98 acts to normally hold the latch 89 in engagement with the notch 90.

When the cylinders are in the position 20 shown in Fig. 5, through the movement of the eccentric bearings 19, which separates the transfer-cylinder 14 from the form-cylinder 13, as hereinbefore shown and described, the further rotation of the transfer-cylinder 25 carries the lug 88 by the outer end 60 and engages the end 87 of the rock-lever 86, since the arrangement is such that the lug 88 engages with the arm 87 only when the cylinders 13 and 14 are separated, the 30 cylinders 14 and 15 being in contact, as shown in Fig. 5; the lug 61 engages the arm 60 when all three cylinders are separated, as shown in Fig. 6. The continued rotation of the transfer-cylinder 14 forces the end 87 35 downwardly and rocks the lever 86 so as to release the latch 89 from the notch 90. This release of the latch 89 causes the shaft 92 to partially rotate contra-clockwise through the pulling action of the coil spring 94, 40 thereby breaking the toggle connection between the shaft 92 and the sliding journal box 82, as shown in Fig. 6, enabling the outward force of the compressed spring 84 to immediately move the transfer-cylinder 14 45 radially away from the impression-cylinder 15 and to throw off the impression. Meanwhile the lug 61, contacting with the arm 60 of the rock-lever 58, has tripped the latch 66 to throw off the inking rolls as has been 50 already set forth when describing the construction shown in Figs. 1, 2 and 3. Therefore, to conclude the cycle of operations, Fig. 6 illustrates this modified embodiment 55 with the three cylinders all separated and the inking rollers 52 out of contact with the form-cylinder 13, the interruption in the feed of the stock having inaugurated the action of the mechanism to throw off the transfer-cylinder from the form-cylinder 13. 60 The latch 89 is reset with its engaging notch 90 by the hand-lever 99 carrying the lug 100 coacting with the lug 101 on the collar 102, mounted on the shaft 102^a. The collar 102 carries the arm 103 connected by the link 65 104 to the arm 105, mounted on the shaft 92.

When the hand-lever 99 is raised to move the arm 103 to the left, the shaft 92 is partially rotated in a clockwise direction, to reset the latch 89 in the notch 90, when the locking engagement is thereafter preserved 70 through the action of the coil spring 98 pulling the lever 86 to the right, slightly outside the path of the lug 88.

By properly positioning the lugs 61 and 88 on the cylinder 14, the successive tripping operations, because of their respective engagements with the rock-levers 58 and 86, through the bodily displacement of the cylinder 14, as before described, can be timed at any intervals desired and in either 80 succession. Furthermore, the position of the lug 61 is such as to accomplish the throwing off of the ink rolls 52, when they are clear of the plate on the form-cylinder 13, thereby securing uniform inking of the 85 entire printing surfaces of the plates.

In the modified embodiment of my invention, illustrated in Figs. 7 and 8, the transfer-cylinder 14 moves obliquely away from the form-cylinder 13, and the impression-cylinder 15 has a right-angled movement away from the transfer-cylinder 14. I employ the same mechanism for throwing off the inking rollers 52, as has been heretofore shown and described with reference to the 95 former constructions illustrated in the preceding figures. In the embodiment shown in Figs. 4, 5 and 6, the transfer-cylinder 14 had two movements at substantially right angles with each other, so as to break off the 100 printing relation of the three cylinders, one from the form-cylinder 13, and the other away from the impression-cylinder 15. In the present embodiment, as shown in Figs. 7 and 8, another construction and arrangement is illustrated, in which the transfer-cylinder 14 has only a single radial movement, controlled by the sheet, away from the 105 form-cylinder 13, as shown in Fig. 8, while remaining in contact with the impression-cylinder 15, while the second or impression throw-off movement is accomplished by moving the impression cylinder 15, its shaft 18 being mounted in eccentric bearings, as 110 shown in these figures.

Referring to this modified form of construction, as shown in Figs. 7 and 8, the shaft 17 of the transfer-cylinder 14 is mounted in the journal-box 106 to slide radially in the ways 107 formed in the frame 12, at 115 substantially right angles to the ways 83 shown in Figs. 4, 5 and 6. This permits a separating movement between the cylinders 13 and 14 without destroying the latter's contact with the impression-cylinder 15. 120 The coil compression spring 108 is secured in the opening 109 in the frame to normally force the journal-box 106 outwardly, so as to separate the cylinder 14 from the cylinder 13. The transfer-cylinder 14 is held in con- 130

tact with the form-cylinder 13 by the stock-controlled tripping and latch mechanism herein described in connection with the construction shown in Figs. 1, 2 and 3, and need not be again described in detail. The journal-box 106 carries the bracket 110 formed on its lower end, which supports the toggle-levers 111 and 112, the lever 112 being pivoted to the pin 113 affixed to the frame 12, as shown. Likewise pivoted to the pin 113 and mounted at substantially right angles to the lever 112, is the arm 114 connected by the link 115 to the arm 26 on the oscillating shaft 27, the construction and operation of which has been heretofore described. The coil spring 116, connecting the arm 114 to the frame, is strained when the toggle-levers 111 and 112 are in their straightened position, as shown in Fig. 7. When the tripping mechanism shown in detail in Figs. 10 and 11, releases the latch 31, the link 115 is moved upwardly in the direction of the arrow shown in Fig. 7, through the force of the spring 116, which likewise breaks the toggle-levers 111 and 112, thereby enabling the compression spring 108 to immediately move the sliding journal-box 106 downwardly, which movement will, at once, separate the transfer-cylinder 14 from the form-cylinder 13, as clearly shown in Fig. 8.

The mechanism for throwing off the inking-rollers 52 in this form of construction (Figs. 7 and 8), after the second or impression throw off is accomplished, is substantially the same in construction and mode of operation as that shown and described in connection with the embodiment illustrated in Figs. 1, 2 and 3, the spring 117, connected to the arm 62 of the rock-lever 58 and to the frame 12, serving to hold the latch 66 in locked engagement with the notch 67 in lieu of the spring 76, as shown in Figs. 1, 2 and 3.

The mechanism for accomplishing the second, or impression throw-off, whereby the impression-cylinder 15 is obliquely swung away and separated from the transfer-cylinder 14, is as follows: The shaft 18 carrying the impression-cylinder 15 is mounted in eccentric bearings 118, which, in turn, are mounted in journals 119 secured to the frame 12. The bearings 118 have arms 120 projecting from flanges on the outside of the frame, as shown. The toggle levers 121 and 122, pivoted at 123, connect the arm 120 with the oscillating shaft 124. The coil spring 125 connects the toggle lever 121 to the frame, this spring being strained when the toggle levers 121 and 122 are straightened, as shown in Figs. 7 and 8. Pivoted at 126 to the lever 122 is the link 127, which affords a rigid connection from the lever 122 to the arm 128, secured on the oscillating shaft 129, journaled in the frame 12, as shown. The shaft 129 carries a collar 130 having a notch 131 cut therein, so formed as to be engaged and

locked in position by the rocking latch-lever 132 pivoted to the frame 12 at 133. The lower end 134 of the latch 132 is so constructed and arranged as to be engaged by the rotating lug 135 mounted on the transfer-cylinder 14, when that cylinder has been displaced and is separated from the form-cylinder 13, the construction shown in Fig. 8, illustrating this feature in the construction with the lug 135 about to engage the end 134 to trip the latch 132, to throw off the impression-cylinder 15 by allowing the spring 125 to break the toggle-levers 121 and 122, to move the link 127 to the left and to swing the arm 120 in the direction shown by the arrow, to move the eccentric bearings 118, thereby separating the cylinder 15 from its printing relation with the cylinder 14. It is obvious that this movement of the eccentric bearings 118 may be accomplished by a suitable spring coiled about the shaft 129, or by any other convenient mechanism actuated by the latch-lever 132, through proper connecting devices.

The latch-lever 132 may be reset in the notch 131 by the hand-lever 136 carrying the lug 137 coacting with the lug 138 on the collar 139 mounted on the shaft 124, thereby rotating the shaft 129 contra-clockwise, and straightening the toggle-levers 121 and 122, while simultaneously placing the spring 125 again under tension. By properly adjusting and positioning the lugs 61 and 135 on the transfer-cylinder 14, the successive tripping operations, through the respective engagements with the trip-levers 58 and 132, can be timed at any intervals desired, and in either succession. However, it is preferable to so arrange the throw-offs so as to cause impression cylinder to throw off before the inking rollers are separated from the form-cylinder, by making such appropriate changes in the arrangement of the trip-levers and their respective coöperating lugs mounted on the transfer-cylinder 14, as will accomplish these successive movements in the order desired, all of which will be readily understood by those skilled in this art.

In Fig. 9 I have shown a still further variation in the mechanism for successively throwing-off the respective cylinders from contact with each with the other, by showing both the transfer-cylinder 14 and the impression-cylinder 15 mounted and operable in eccentric bearings. In this construction, the eccentric bearings 19 for the transfer-cylinder 14, are first actuated, as shown in Fig. 2, by the tripping mechanism controlled by the absence or interruption of the feed of the stock 37 on the feed-table 36, this initial movement separating only the transfer-cylinder 14 from the form-cylinder 13; the second eccentric movement is operable by the lug 135 mounted on the transfer-cylinder 14, now separated from the form-

cylinder 13, engaging with the latch-lever 132 to throw off the impression-cylinder 15 from the transfer-cylinder 14, as has been heretofore described with relation to the 5 construction shown in Figs. 7 and 8. Thereafter the lug 61 trips the rock-lever 58 to release the latch 66, which controls the operation of the mechanism for throwing off the inking rollers, as has been already described in connection with the construction 10 shown in Figs. 1, 2 and 3.

It is apparent that the impression-cylinder 15 may be initially separated from the transfer-cylinder 14, in the cycle of operations of the press, in which case the lugs 61 and 135 would be suitably mounted upon the impression-cylinder 15, and the respective trip-lever mechanisms operable through engagement with these lugs, would be so arranged 15 in proper relation thereto as to insure the predetermined succession of throw-offs in the press.

In the embodiments of my invention shown in Figs. 12 and 13, I have illustrated 20 forms of off-set presses in which, in each case, the actuating lug is mounted on a cylinder which is not affected by the initial throw-off movement.

In the construction shown in Fig. 12, the 25 transfer-cylinder 14 is alone mounted and operable in eccentric bearings 19, as shown in Figs. 1, 2 and 3. In this form, the eccentric bearings 19 are first actuated, as shown in Fig. 2, by the tripping mechanism 30 controlled by the absence or interruption of the feed of the stock 37 on the feed-table 36, or manually-operated means may be used to inaugurate this initial movement, which separates the transfer-cylinder 14 from both 35 form-cylinder 13 and impression-cylinder 15, as already set forth. Mounted on the pin 136 on the outside of the frame 12 is the lever 137, the upper arm of which has the slotted bearing 138 adapted to engage with the stud or pin 139 on the end of the shaft 17. The lower arm 140 (shown in dotted 40 lines) of the lever 137 is on the inside of the frame 12, and carries, on the pivot 141, the rock-lever 142, the outer end 143 of which 45 lever 142 is adapted to engage the lug 144 mounted on the impression-cylinder 15 when the lever 137 is oscillated through the separation of the transfer-cylinder 14 from the other two cylinders 13 and 14 just described.

50 The other arm 145 of the lever 142, is connected by the link 146 to the lever 64, which operates the latch 66 in the notch 67, to throw off the inking rollers 52 from the form-cylinder 13, all as has been hereinbefore described in connection with the construction and operation of the presses shown in Figs. 1, 2 and 3.

In the construction shown in Fig. 13, the impression-cylinder 15 is alone mounted and 55 operable in eccentric bearings 118, as in the

forms shown in Figs. 7, 8 and 9. In this Fig. 13 construction, the eccentric bearings 118 are first operated by the tripping mechanism heretofore shown and described, or by manual means, so as to separate the impression-cylinder 15 from the transfer-cylinder 14. This may be accomplished by the following mechanism: Mounted on the arm 120 is the toggle lever 147 pivoted at 148 to the other toggle lever 149, which is pivotally mounted on the pin 150 secured to the frame 12. The lever 149 is connected by the link 151 to the arm 152 carried on the rock-shaft 27. The compression spring 153 is secured between the lever 149 and the frame, 70 and breaks the toggle levers 147 and 149 from their straightened position, as shown, to move the arm 120 to the left, whenever the latch 31 is released from the notch 34 in the sleeve 35 mounted on the shaft 27. 75 Pivoted on the pin 154 on the outside of the frame 12 is the lever 155, the upper arm of which has the slotted bearing 156 adapted to engage with the stud or pin 157 on the end of the shaft 18. The lower arm 158 (shown in dotted lines) of the lever 155 is on the inside of the frame 12, and carries on the pivot 159 the rock-lever 160, the outer end 161 of which lever 160 is adapted to engage the lug 162 mounted on the transfer-cylinder 95 14, when the lever 155 is oscillated through the separation of the impression-cylinder 15 from the transfer-cylinder 14, as has been already described. The other end 163 of the lever 160 is connected by the link 164 to the lever 64 which operates the latch 66 in the notch 67 to throw off the inking rollers 52 from the form-cylinder, all as has been already set forth in connection with Figs. 1, 2 and 3.

100 The foregoing constructions all embody the principles of my invention as applied to "off-set" presses, but it is obvious that my invention is applicable to other forms of printing-presses, and that other combinations and modes of operation may be made; the foregoing being sufficient to disclose the underlying principles and advantages involved. The actuating lugs or other engaging members are preferably disposed and 105 mounted on the different coating printing members constituting the press, yet they may be arranged and operable upon other parts of the press, so as to insure the predetermined sequence of operations desired, so long 110 as they are disposed to be thrown into the path of some intermediate device, the operation of which is controlled and inaugurated by the initial movement in the press.

115 I claim as my invention:—

120 1. In a printing-press having a form-cylinder, a transfer-cylinder and an impression-cylinder, inking mechanism for the form-cylinder, means for separating the cylinders to throw off the impression, and means for 125 130

throwing off the inking mechanism normally held in inoperative position and placed in operative position by the separation of said cylinders.

- controlled by the stock, means for separating the transfer-cylinder from the impression-cylinder controlled by means operable by said separated transfer-cylinder, and automatic means for throwing off the inking mechanism controlled by one of said cylinder separating means.
14. In a printing-press having a form-cylinder, a transfer-cylinder and an impression-cylinder, inking mechanism for the form-cylinder, means for separating the transfer-cylinder from the form-cylinder controlled by the stock, means for separating the transfer-cylinder from the impression-cylinder controlled by means operable by said separated transfer-cylinder, and automatic means for thereafter throwing off the inking mechanism controlled by one of said cylinder separating means.
15. In a printing-press having a form-cylinder, a transfer-cylinder and an impression-cylinder, inking mechanism for the form-cylinder, means for separating the transfer-cylinder from the form-cylinder controlled by the stock, means for separating the transfer-cylinder from the impression-cylinder controlled by means operable by said separated transfer-cylinder, and automatic means for throwing off the inking mechanism controlled by one of said cylinder separating means.
16. In a printing-press having a form-cylinder, a transfer-cylinder and an impression-cylinder, inking mechanism for the form-cylinder, means for separating the transfer-cylinder from the form-cylinder controlled by the stock, means for separating the transfer-cylinder from the impression-cylinder controlled by means operable by said separated transfer-cylinder, and automatic means for thereafter throwing off the inking mechanism controlled by one of said cylinder separating means and actuated by the further rotation of the press.
17. In a printing-press having a form-cylinder, a transfer-cylinder and an impression-cylinder, inking mechanism for the form-cylinder, means for separating the transfer-cylinder and the form-cylinder while maintaining the transfer and impression cylinders in printing relation, means for separating the impression-cylinder and the transfer-cylinder, and means for throwing off the inking mechanism normally held in inoperative position and placed in operative position by one of said separated cylinders.
18. In a printing-press having a form-cylinder, a transfer-cylinder and an impression-cylinder, inking mechanism for the form-cylinder, means for separating the transfer-cylinder and the form-cylinder, controlled by the stock, while maintaining the transfer and impression cylinders in printing relation, means for separating the impression-cylinder and the transfer-cylinder controlled by one of said separated cylinders.
19. In a printing-press having a form-cylinder, a transfer-cylinder and an impression-cylinder, inking mechanism for the form-cylinder, means for separating the transfer-cylinder and the form-cylinder while maintaining the transfer and impression cylinders in printing relation, means for separating the impression-cylinder and the transfer-cylinder, controlled by one of said separated cylinders.
20. In a printing-press having a form-cylinder, a transfer-cylinder and an impression-cylinder, inking mechanism for the form-cylinder, means for separating the transfer-cylinder and the form-cylinder, controlled by the stock, while maintaining the transfer and impression cylinders in printing relation, means for separating the impression-cylinder and the transfer-cylinder controlled by one of said separated transfer-cylinder, and means for throwing off the inking mechanism controlled by one of said cylinder-separating means.
21. In a printing-press having a form-cylinder, a transfer-cylinder and an impression-cylinder, inking mechanism for the form-cylinder, means for separating the transfer-cylinder and the form-cylinder while maintaining the transfer and impression cylinders in printing relation, means for thereafter separating the impression-cylinder and the transfer-cylinder controlled by means operable by said separated transfer-cylinder, and means for throwing off the inking mechanism controlled by one of said cylinder-separating means.
22. In a printing-press having a form-cylinder, a transfer-cylinder and an impression-cylinder, inking mechanism for the form-cylinder, means for separating the transfer-cylinder and the form-cylinder controlled by the stock, while maintaining the transfer and impression cylinders in printing relation, means for thereafter separating the impression-cylinder and the transfer-cylinder controlled by means operable by said separated transfer cylinder, and means for throwing off the inking mechanism controlled by one of said cylinder-separating means.
23. In a printing-press having a form-cylinder, a transfer-cylinder and an impression-cylinder, inking mechanism for the form-cylinder, means for separating the transfer-cylinder and the form-cylinder

while maintaining the transfer and impression cylinders in printing relation, automatic means for separating the impression-cylinder and the transfer cylinder, and automatic means for throwing off the inking mechanism normally held in inoperative position and placed in operative position by one of said separated cylinders.

24. In a printing-press having a form-cylinder, a transfer-cylinder and an impression cylinder, inking mechanism for the form-cylinder, means for separating the transfer-cylinder and the form-cylinder while maintaining the transfer and impression-cylinders in printing relation, automatic means for thereafter separating the impression cylinder and the transfer-cylinder, and automatic means for throwing off the inking mechanism normally held in inoperative position and placed in operative position by one of said separated cylinders.

25. In a printing-press having a form-cylinder, a transfer-cylinder and an impression-cylinder, inking mechanism for the form-cylinder, means for separating the transfer-cylinder and the form-cylinder while maintaining the transfer and impression cylinders in printing relation, automatic means for separating the impression-cylinder and the transfer-cylinder controlled by means operable by said separated transfer-cylinder, and automatic means for throwing off the inking mechanism controlled by one of said cylinder-separating means.

26. In a printing-press having a form-cylinder, a transfer-cylinder and an impression-cylinder, inking mechanism for the form-cylinder, means for separating the transfer-cylinder and the form-cylinder, controlled by the stock, while maintaining the transfer and impression cylinders in printing relation, automatic means for separating the impression-cylinder and the transfer-cylinder controlled by means operable by said separated transfer-cylinder, and automatic means for throwing off the inking mechanism controlled by one of said cylinder-separating means.

50 27. In a printing-press having a form-cylinder, a transfer-cylinder and an impression-cylinder, inking mechanism for the form-cylinder, means for separating the transfer-cylinder and the form-cylinder
55 while maintaining the transfer and impression cylinders in printing relation, automatic means for thereafter separating the impression-cylinder and the transfer-cylinder controlled by means operable by said
60 separated transfer-cylinder, and automatic means for throwing off the inking mechanism controlled by one of said cylinder-separating means.

28. In a printing-press having a form-
65 cylinder, a transfer-cylinder and an impres-

sion cylinder, inking mechanism for the form-cylinder, means for separating the transfer-cylinder and the form-cylinder controlled by the stock, while maintaining the transfer and impression cylinders in printing relation, automatic means for thereafter separating the impression-cylinder and the transfer-cylinder controlled by means operable by said separated transfer-cylinder, and automatic means for throwing off the inking mechanism controlled by one of said cylinder-separating means. 70 75

29. In a printing-press having a form-cylinder, a transfer-cylinder and an impression-cylinder, inking mechanism for the 80 form-cylinder, means for separating the transfer-cylinder and the form-cylinder automatically controlled by the stock, while maintaining the transfer and impression cylinders in printing relation, means for thereafter separating the impression-cylinder and the transfer-cylinder, operable through the further rotation of the press, and means for throwing off the inking mechanism controlled by one of said cylinder-separating 85 means. 90

30. In a printing-press having a form-cylinder, a transfer-cylinder and an impression-cylinder, inking mechanism for the form-cylinder, means for separating the transfer-cylinder and the form-cylinder automatically controlled by the stock, while maintaining the transfer and impression cylinders in printing relation, means for thereafter separating the impression-cylinder and the transfer-cylinder, operable through the further rotation of the press, and means for thereafter throwing off the inking mechanism controlled by one of said cylinder-separating means. 95 100 105

31. In a printing-press having a form-cylinder, a transfer-cylinder and an impression-cylinder, inking mechanism for the form-cylinder, means for separating the transfer-cylinder and the form-cylinder 110 automatically controlled by the stock, while maintaining the transfer and impression cylinders in printing relation, means for thereafter separating the impression-cylinder and the transfer-cylinder, and means for throwing off the inking mechanism controlled by one of said cylinder-separating means and also through the further rotation 115 of the press.

32. In a printing-press having a form-cylinder, a transfer-cylinder and an impression-cylinder, inking mechanism for the form-cylinder, means for separating the transfer-cylinder and the form-cylinder automatically controlled by the stock, while maintaining the transfer and impression cylinders in printing relation, means for thereafter separating the impression-cylinder and the transfer-cylinder, and means for thereafter throwing off the inking mechanism 130

- nism controlled by one of said cylinder-separating means and also through the further rotation of the press.
33. In a printing-press having a form-cylinder, a transfer-cylinder and an impression-cylinder, inking mechanism for the form-cylinder, means for separating the transfer-cylinder and the form-cylinder automatically controlled by the stock, while
- 5 10 15 20 25 30 35 40 45 50 55 60 65
- maintaining the transfer and impression cylinders in printing relation, means for thereafter separating the impression-cylinder and the transfer-cylinder, and means for throwing off the inking mechanism controlled by one of said cylinder-separating means, both of said last mentioned means being operable in predetermined succession through the further rotation of the press.
34. In a printing-press having a form-cylinder, a transfer-cylinder and an impression-cylinder, inking mechanism for the form-cylinder, means for separating the transfer-cylinder and the form-cylinder automatically controlled by the stock, while
- 70 75 80 85 90 95 100 105 110 115 120 125 130
- maintaining the transfer and impression cylinders in printing relation, means for thereafter separating the impression-cylinder and the transfer-cylinder, and means for thereafter throwing off the inking mechanism controlled by one of said cylinder-separating means, both of said last mentioned means being operable in predetermined succession through the further rotation of the press.
35. In a printing-press having a form-cylinder, a transfer-cylinder and an impression-cylinder, inking mechanism for the form-cylinder, means, comprising a spring-actuated trip and latch mechanism, controlled by the stock, for separating the cylinders to throw off the impression, and means for throwing off the inking mechanism normally held in inoperative position and placed in operative position by the separation of said cylinders and actuated through the further rotation of the press.
36. In a printing-press having a form-cylinder, a transfer-cylinder and an impression-cylinder, inking mechanism for the form-cylinder, means, comprising a spring-actuated trip and latch mechanism, controlled by the stock, for separating the cylinders to throw off the impression, and automatic means for throwing off the inking mechanism normally held in inoperative position and placed in operative position by the separation of said cylinders and actuated through the further rotation of the press.
37. In a printing-press having a form-cylinder, a transfer-cylinder and an impression-cylinder, inking mechanism for the form-cylinder, means for separating the transfer-cylinder from both form-cylinder and impression-cylinder controlled by the
- stock, and means operable through the further rotation of the separated transfer-cylinder for throwing off the inking mechanism from the form-cylinder.
38. In a printing-press having a form-cylinder, a transfer-cylinder and an impression-cylinder, inking mechanism for the form-cylinder, means for separating the transfer-cylinder from both form-cylinder and impression-cylinder controlled by the stock, and automatic means operable through the further rotation of the separated transfer-cylinder for throwing off the inking mechanism from the form-cylinder.
39. In a printing-press having a form-cylinder, a transfer-cylinder and an impression-cylinder, inking mechanism for the form-cylinder, means for separating the transfer-cylinder from the form-cylinder controlled by the stock, means for separating the transfer-cylinder from the impression-cylinder operable through the further rotation of the separated transfer-cylinder, and means for throwing off the inking mechanism from the form-cylinder, controlled by other means rotatable in conjunction with the separated transfer-cylinder.
40. In a printing-press having a form-cylinder, a transfer-cylinder and an impression-cylinder, inking mechanism for the form-cylinder, means for separating the transfer-cylinder from the form-cylinder controlled by the stock, means for separating the transfer-cylinder from the impression-cylinder operable through the further rotation of the separated transfer-cylinder, and means for thereafter throwing off the inking mechanism from the form-cylinder, controlled by other means rotatable in conjunction with the separated transfer-cylinder.
41. In a printing-press having a form-cylinder, a transfer-cylinder and an impression-cylinder, inking mechanism for the form-cylinder, means for separating the transfer-cylinder from the form-cylinder controlled by the stock, means for separating the transfer-cylinder from the impression-cylinder operable through the further rotation of the separated transfer-cylinder, and means for throwing off the inking mechanism from the form-cylinder, controlled by other means rotatable in conjunction with the separated transfer-cylinder through the further rotation of the press.
42. In a printing-press having a form-cylinder, a transfer-cylinder and an impression-cylinder, inking mechanism for the form-cylinder, means for separating the transfer-cylinder from the form-cylinder controlled by the stock, means for separating the transfer-cylinder from the impression-cylinder operable through the further rotation of the separated transfer-cylinder, and means for thereafter throwing off the inking mechanism from the form-cylinder.

ing mechanism from the form-cylinder, controlled by other means rotatable in conjunction with the separated transfer-cylinder through the further rotation of the press.

form-cylinder, means for separating the transfer-cylinder from the form-cylinder controlled by the stock, means for separating the transfer-cylinder from the impression-cylinder, and means for throwing off the inking mechanism from the form-cylinder controlled by one of said cylinder-separating means, said two last-mentioned means being controlled by other means rotatable in conjunction with the separated transfer-cylinder. 70 75

48. In a printing-press having a form-cylinder, a transfer-cylinder and an impression-cylinder, inking mechanism for the form-cylinder, means for separating the transfer-cylinder from the form-cylinder controlled by the stock, means for separating the transfer-cylinder from the impression-cylinder, and means for thereafter throwing off the inking mechanism from the form-cylinder controlled by one of said cylinder-separating means, said two last-mentioned means being controlled by other means rotatable in conjunction with the separated transfer-cylinder. 90 85

49. In a printing-press having a form-cylinder, a transfer-cylinder and an impression-cylinder, inking mechanism for the form-cylinder, means for separating the transfer-cylinder from the form-cylinder 95 controlled by the stock, means for separating the transfer-cylinder from the impression-cylinder, and means for throwing off the inking mechanism from the form-cylinder controlled by one of said cylinder-separating 100 means, said two last-mentioned means being controlled by other means rotatable in conjunction with the separated transfer-cylinder through the further rotation of the press.

50. In a printing-press having a form-cylinder, a transfer-cylinder and an impression-cylinder, inking mechanism for the form-cylinder, means for separating the transfer-cylinder from the form-cylinder controlled by the stock, means for separating the transfer-cylinder from the impression-cylinder, and means for thereafter throwing off the inking mechanism from the form-cylinder controlled by one of said cylinder-separating means, said two last-mentioned means being controlled by other means rotatable in conjunction with the separated transfer-cylinder through the further rotation of the press. 105 110 115

51. In a printing-press having a form-cylinder, a transfer-cylinder and an impression-cylinder, inking mechanism for the form-cylinder, means for separating the transfer-cylinder from the form-cylinder controlled by the stock, automatic means for separating the transfer-cylinder from the impression-cylinder, and automatic means for throwing off the inking mechanism from the form-cylinder controlled by one of said cylinder-separating means, said two last- 130

mentioned means being controlled by other means rotatable in conjunction with the separated transfer-cylinder.

52. In a printing-press having a form-cylinder, a transfer-cylinder and an impression-cylinder, inking mechanism for the form-cylinder, means for separating the transfer-cylinder from the form-cylinder controlled by the stock, automatic means for 10 separating the transfer-cylinder from the impression-cylinder, and automatic means for thereafter throwing off the inking mechanism from the form-cylinder controlled by one of said cylinder-separating means, said 15 two last-mentioned means being controlled by other means rotatable in conjunction with the separated transfer-cylinder.
53. In a printing-press having a form-cylinder, a transfer-cylinder and an impression-cylinder, inking mechanism for the form-cylinder, means for separating the transfer-cylinder from the form-cylinder controlled by the stock, automatic means for 20 separating the transfer-cylinder from the impression-cylinder, and automatic means for throwing off the inking mechanism from the form-cylinder controlled by one of said cylinder-separating means, said two last-mentioned means being controlled by other 25 means rotatable in conjunction with the separated transfer-cylinder through the further rotation of the press.

54. In a printing-press having a form-cylinder, a transfer-cylinder and an impression-cylinder, inking mechanism for the form-cylinder, means for separating the transfer-cylinder from the form-cylinder controlled by the stock, automatic means for separating the transfer-cylinder from the impression-cylinder, and automatic means 30 for thereafter throwing off the inking mechanism from the form-cylinder controlled by one of said cylinder-separating means, said two last-mentioned means being controlled by other 35 means rotatable in conjunction with the separated transfer-cylinder through the further rotation of the press.

55. In a printing-press comprising two members constituting a printing couple, an inking mechanism therefor, means for moving one of said members to throw off the impression, means for throwing off the inking mechanism, and means carried by said moved member to actuate said last-mentioned means at a predetermined point in the cycle of operation after the impression is thrown off.

56. In a printing-press comprising two members constituting a printing couple, an inking mechanism therefor, means for moving one of said members to throw off the impression, means for throwing off the inking mechanism, and means carried by said moved member to actuate said last-men-

tioned means at a predetermined point in the cycle of operation after the impression is thrown off, operable through the further movement of the press.

57. In a printing-press, a printing member and impression member constituting with 70 said first member a printing couple, an inking mechanism therefor, means for changing the path of movement of one of said members to throw off the impression, and automatic means operable by said moved 75 member in the further movement of the press to throw off the inking mechanism.

58. In a printing-press, a printing member and impression member constituting with said first member a printing couple, an 80 inking mechanism therefor, means for changing the path of movement of one of said members to throw off the impression, and automatic means operable by said moved member in the further movement of 85 the press to throw off the inking mechanism at a predetermined point.

59. In a printing-press, a printing member and impression member, an inking mechanism therefor, means for moving one 90 of said members out of its normal path, a third member placed in operative position by said movement, and means thereafter actuated by said third member to throw off the inking mechanism. 95

60. In a printing-press, a printing member and impression member, an inking mechanism therefor, means for moving one of 100 said members out of its normal path, a third member placed in operative position by said movement, and means thereafter actuated by said third member, and operable through the further movement of the press, to throw off the inking mechanism.

61. In a printing-press comprising two 105 members constituting a printing couple, an inking mechanism therefor, a third member having a normal path of movement, controlled by one of said printing members for changing said path of movement of said 110 third member, and means for throwing off said inking mechanism operable by said third member while out of its normal path of movement.

62. In a printing-press comprising two 115 members constituting a printing couple, an inking mechanism therefor, a third member having a normal path of movement, means controlled by one of said printing members for changing said path of movement of said third member, and means for throwing off said inking mechanism operable by said third member while out of its 120 normal path of movement through the further movement of the press.

63. In a printing-press, a plurality of printing members, inking mechanism therefor, normally inoperative means for throw-

- ing off said inking mechanism, a constantly moving actuating member controlled by one of said printing members, and means for changing the path of movement of said printing member to bring said actuating member into operative relation with said normally inoperative means. 65
64. In a printing-press, a plurality of printing members, inking mechanism therefor, normally inoperative means for throwing off said inking mechanism, a constantly moving actuating member controlled by one of said printing members, and means for changing, at a predetermined point, the path of movement of said printing member to bring said actuating member into operative relation with said normally inoperative means. 70
65. In a printing-press, a plurality of printing members, inking mechanism therefor, normally inoperative means for throwing off said inking mechanism, a constantly moving actuating member controlled by one of said printing members, and means for changing the path of movement of said printing member to bring said actuating member into operative relation with said normally inoperative means through the further movement of the press. 75
66. In a printing-press, a plurality of printing members, inking mechanism therefor, normally inoperative means for throwing off said inking mechanism, a constantly moving actuating member controlled by one of said printing members, and means for changing, at a predetermined point, the path of movement of said printing member to bring said actuating member into operative relation with said normally inoperative means through the further movement of the press. 80
67. In a printing-press having two members constituting a printing couple, an inking mechanism therefor, means for separating the printing members, and means for thereafter throwing off the inking mechanism normally held in inoperative position and placed in operative position by one of said separated members and actuated by the further movement of the press. 85
68. In a printing-press having a plurality of coacting members including a printing couple, an inking mechanism therefor, means for changing the relative position of one of said members, and means for thereafter throwing off the inking mechanism normally held in inoperative position and placed in operative position by said changed member and actuated by the further movement of the press. 90
69. In a printing-press having two or more coacting members, an inking mechanism therefor, means for separating two of said coacting members, means for throwing off said inking mechanism, and means controlled by one of said separated members for thereafter actuating said last mentioned means. 95
70. In a printing-press having two or more coacting members, an inking mechanism therefor, means for separating two of said coacting members, means for throwing off said inking mechanism, and means controlled by one of said separated members for thereafter actuating said last-mentioned means through the further movement of the press. 100
71. In a printing-press having a form member, a transfer member and an impression member, inking mechanism for the form member, means for separating two of said members, and means for thereafter throwing off the inking mechanism normally held in inoperative position and placed in operative position by one of said separated members and actuated by the further movement of the press. 105
72. In a printing-press having a form member, a transfer member and an impression member, inking mechanism for the form member, means for separating two of said members, and automatic means for throwing off the inking mechanism normally held in inoperative position and placed in operative position by one of said separated members and actuated by the further movement of the press. 110
73. In a printing-press having a form member, a transfer member and an impression member, inking mechanism for the form member, means for moving one of said members out of printing relation, and automatic means controlled by said separated member for thereafter separating the other said members and for throwing off the inking mechanism. 115
74. In a printing-press having a form member, a transfer member and an impression member, inking mechanism for the form member, means for moving one of said members out of printing relation, and automatic means controlled by said separated member for thereafter separating the other said members and for throwing off the inking mechanism, both at predetermined points. 120
75. In a printing-press having a form member, a transfer member and an impression member, inking mechanism for the form member, means for moving one of said members out of printing relation, and automatic means for thereafter separating the other said members and for throwing off the inking mechanism controlled and actuated by further movement of the press, dependent upon the operation of said first-mentioned means. 125
76. In a printing-press having a form member, a transfer member and an impres-

- sion member, inking mechanism for the form member, means for moving one of said members out of printing relation, and automatic means for thereafter separating the other 5 said members and for throwing off the inking mechanism controlled, at a predetermined point, and actuated by the further movement of the press, dependent upon the operation of said first-mentioned means.
- 10 77. In a printing-press having a form member, a transfer member and an impression member, inking mechanism for the form member, means for moving one of the members out of printing relation, automatic 15 means controlled by said separated member for throwing off the inking mechanism, and other automatic means also controlled by said separated member for separating the other said members.
- 20 78. In a printing-press having a form member, a transfer member and an impression member, inking mechanism for the form member, means for moving one of the members out of printing relation, automatic 25 means controlled by said separated member for throwing off the inking mechanism, and other automatic means also controlled by said separated member for separating the other said members through the further 30 movement of the press.
79. In a printing-press having a form member, a transfer member and an impression member, inking mechanism for the form member, means for moving one of said members out of printing relation, means for throwing off the inking mechanism, and means for separating the other said members controlled by said inking throw-off means and actuated by the further 35 movement of the press.
80. In a printing-press, a plurality of printing members, an inking mechanism therefor, means for separating two of said members, normally inoperative means for throwing off said inking mechanism, and means controlled by one of said printing members for placing said normally inoperative means in operative position to throw off said inking mechanism.
- 45 81. In a printing-press, a plurality of printing members, an inking mechanism therefor, means for separating two of said members, normally inoperative means for throwing off said inking mechanism, and means controlled by one of said printing members for placing said normally inoperative means in operative position to throw off said inking mechanism through the further 50 movement of the press.
- 55 82. In a printing-press, a plurality of printing members, an inking mechanism therefor, means for throwing off the impression, means for throwing off the inking mechanism normally held in inoperative position, and means controlled by one of said 60 members for placing said last-mentioned means in operative position to throw off said inking mechanism.
83. In a printing-press, a plurality of printing members, an inking mechanism therefor, means for throwing off the impression, means for throwing off the inking mechanism normally held in inoperative position, and means controlled by one of said members for placing, at a predetermined point, said last-mentioned means in operative position to throw off said inking mechanism.
84. In a printing-press, a plurality of printing members, an inking mechanism therefor, means for separating two of said members, and means for throwing off said inking mechanism normally held in inoperative position but movable into operative position by said separation, said inking throw-off means being subsequently actuated by one of said separated printing members.
85. In a printing-press, a plurality of printing members, an inking mechanism therefor, means for separating two of said members, and means for throwing off said inking mechanism normally held in inoperative position but movable into operative position by said separation, said inking throw-off means being subsequently actuated by one of said separated printing members at a predetermined point.
86. In a printing-press comprising a plurality of printing members two of which constitute a printing couple, means for separating the members of the printing couple, normally inoperative means for separating the other member from its coacting member in said couple, means controlled by one of the members of the separated printing couple for changing the position of said normally inoperative means, and means operated through the further movement of the press for actuating said second separating means.
87. In a printing-press comprising a plurality of printing members two of which constitute a printing couple, means for separating the members of the printing couple, normally inoperative means for separating the other member from its coacting member in said couple, means controlled by one of the members of the separated printing couple for changing, at a predetermined point, the position of said normally inoperative means, and means operated through the further movement of the press for actuating said second separating means.
88. In a printing-press, a printing member and impression member, an inking mechanism therefor, means for moving one of said members out of its normal path, a third member placed in operative position by said movement, and automatic means controlled 120

and thereafter actuated by said third member to throw off the inking mechanism.

89. In a printing-press, a printing member and impression member, an inking mechanism therefor, means for moving one of said members out of its normal path, a third member placed in operative position by said movement, and means controlled and thereafter actuated by said third member, 10 and operable through the further movement of the press, to throw off the inking mechanism at a predetermined point.

90. In a printing-press, a plurality of printing members, inking mechanism therefor, normally inoperative means for throwing off the inking mechanism, a constantly moving member carried by one of said printing members to actuate said inking throwing-off means, and means for separating said 20 printing members to bring said actuating member into operative relation with said normally inoperative means.

91. In a printing-press, a plurality of printing members, inking mechanism therefor, normally inoperative means for throwing off the inking mechanism, a constantly moving member carried by one of said printing members to actuate said inking throwing-off means, and means for separating said 30 printing members to bring said actuating member into operative relation with said normally inoperative means through the further movement of the press.

92. In a printing-press, a plurality of

printing members, an inking mechanism 35 therefor, means for separating two of said members, normally inoperative means for throwing off said inking mechanism, and an actuating member controlled and carried by one of said printing members for placing 40 at a predetermined point said normally inoperative means in operative position to throw off said inking mechanism through the further movement of the press.

93. In a printing-press having a form-cylinder, a transfer-cylinder and an impression-cylinder, inking mechanism for the form-cylinder, means for separating the transfer-cylinder from both form-cylinder and impression-cylinder, and means oper- 50 able through the further rotation of the separated transfer-cylinder for throwing off the inking mechanism from the form-cylinder.

94. In a printing-press having a form-cylinder, a transfer-cylinder and an impression-cylinder, inking mechanism for the form-cylinder, means for separating the transfer-cylinder from both form-cylinder and impression-cylinder, and automatic 60 means operable through the further rotation of the separated transfer-cylinder for throwing off the inking mechanism from the form-cylinder.
